US0D1105655S

(12) **United States Design Patent** (10) **Patent No.:** **US D1,105,655 S**
(45) **Date of Patent:** **** Dec. 9, 2025**

(54) **WIRELESS ELECTRONIC FENCE DEVICE**

(71) Applicant: **SHENZHEN WELLTURN TECHNOLOGY CO., LTD.**,
Guangdong (CN)

(72) Inventor: **Xiai Yuan**, Guangdong (CN)

(73) Assignee: **SHENZHEN WELLTURN TECHNOLOGY CO., LTD.**, Shenzhen (CN)

(**) Term: **15 Years**

(21) Appl. No.: **29/967,914**

(22) Filed: **Oct. 14, 2024**

(30) **Foreign Application Priority Data**

(57) **CLAIM**

The ornamental design for a wireless electronic fence device as shown and described.

DESCRIPTION

FIG. 1 is a perspective view of a wireless electronic fence device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the wireless electronic fence device that form no part of the claimed design.
